ARTICLE OF MANUFACTURE IN A COMBINED RADIO CABINET AND SOUND AMPLIFYING DEVICE

Application filed May 31, 1929. Serial No. 367,214.

One object of my invention is to provide a rigid and sturdy radio cabinet providing an accessible top compartment with ample space for any radio chassis, speaker, batteries and other apparatus or devices required in connection therewith, and wherein all such devices and parts are entirely concealed from view.

The principal object of my invention, however, is to provide a radio cabinet that would not only serve as a housing for the radio set and its various parts, but would also combine ingeniously all advantages of a satisfactory reproducing element—and the improved quality of sound provided by the use of a special sounding board and sounding chamber.

I attain these objects by the peculiar design and construction of the cabinet and its component baffle board illustrated in the accompanying drawing, in which—

Figure 1 is a perspective view of my improved cabinet,

Figure 2 is a sectional elevation taken on the line 2—2 of Figure 1,

Figure 3 is a front view of an auxiliary baffle board for use with loud speakers which operate efficiently only when standing in a vertical position, and

Figure 4 is a fragmentary view of the cabinet with said auxiliary baffle board in place.

Similar numerals refer to like parts throughout the several views.

5 indicates the baffle or sounding board which also forms the bottom of the cabinet proper, 6 indicates the front panel of the cabinet, which panel readily admits attachment of the radio control operating mechanism and on which is shown mounted the radio dial 7, and switch levers 8. Below the panel 6 is a transparent cover 9 such as glass or celluloid, affixed to the cabinet base 12, a space or slot 11 between the two forming a receptacle for the insertion of a card or strip form 10 comprising a ready reference list or directory of radio stations.

The cabinet side walls 13 are reinforced by standards 14 evenly disposed around the cabinet, the side wall being of light construction, this mode of construction having the effect of

materially supplementing the tonal quality of the sounding board. 15 is a cover hinged to the body of the cabinet in the usual manner. In the baffle board 5, I form a circular opening or aperture 16 over which is placed the loud speaker 17 of the radio instrument, the radio receiving set being shown as 18. To vary the tone and volume of the sound emitted from within the cabinet, I provide a shutter 19 normally held in position so as not to overlap or close said aperture 16 by a spring 20, the said shutter 19 being held in a pivoted position by means of a pin 21 secured to the baffle board, and has a lever 23 extending past said pivot pin 21, one end of the spring 20 being attached to said pivot pin 21, the other end being fastened to the baffle board by a suitable bolt 22.

The lever 23 is pivotably attached to the cabinet as at 24, linked to the shutter 19 by 70 the link 25 and link pins 26 and 27. 28 is a toothed rack into which the lever 23 is designed to engage near its outwardly extended end, and by means of which the shutter 19 is held over the aperture 16 at any desired degree, or to close the same entirely. A slot 29 re-inforced in the baffle board 5 provides an engaging means for the finger 30 of an auxiliary baffle or sound board 31 required when the loud speaker as indicated in 32 must be 80 placed in a vertical position, the cabinet proper being supported in upright position and off the floor by means of leg or pedestal members 33.

As a practical article of manufacture, the 85 cabinet is built of any suitable hardwood or veneer in combination. In its design, it not only embodies an attractive compact unit for housing the radio chassis and entirely concealing the same from view, but lends itself 90 readily to form a most suitable ladies desk, a mere structural arrangement of the front of the cabinet permitting its adaptation to this purpose; and it is obvious that said front portion also lends itself to the incorporation 95 of other features, the radio station directory as herein before mentioned and other purposes for which it may be appropriate.

Because of the vital part played by the sound chamber of all musical instruments, 100

consider that of the violin case or grand piano, for example, the design of my cabinet along the lines of the latter in conjunction with my baffle board and the location of the 5 sound eliminating aperture therein, I create an outstanding sound amplifier.

Experiments have amply demonstrated the best position for the aperture, the resulting effect being the reproduction of the human 10 voice and instrumental tone of a practically uniform quality. From the deep voiced tuba of an orchestra to the softest note of a vocal solo—every tone—every sound is reproduced in all its beauty, as nearly perfect as human 15 ingenuity and mechanical contrivances will allow.

Unlike most all radio cabinets, I employ no grille, use no metal screen, cloth or other substance to cover the opening from which the 20 sound is emitted, said unobstructed opening thus eliminating sound resistance and assuring a clear and positive volume of sound. Located at the bottom of the cabinet, the opening is not even brought to view. There 25 are no corners or angles to create a resistance, hence the sound is free to travel over an unbroken area until it contacts with the floor from which it rebounds with a fidelity, breadth, and magnificence of tone practically 30 free from distortion, the design and method of constructing the cabinet in a large measure being responsible for this.

Supplementing by a secondary control for increasing or decreasing the volume of tone, 35 as all radio instruments are equipped, my cabinet provides an adequate additional means for attaining selectivity in volume when occasion requires.

While I have omitted for the sake of simplicity, illustrations showing further adaptations or modifications, it should be understood that these are possible, and in practice, the design of the cabinet can be considerably cheapened or enriched as is common in the 40 furniture art. I am also aware that slight modifications may from time to time be made in the details of construction illustrated without departing, however, from the scope of the present invention as herein set forth, and 45 as defined in the claims which are appended hereto. Hence, I do not limit my present invention to the exact description or construction herein disclosed, but what I do claim, 50 is:—

55 1. In a radio apparatus and sound amplifying unit comprising an irregular shaped hollow body with a bottom having an aperture and a hingably affixed top, leg members attached to said body for holding the same 60 above the floor, said bottom comprising a baffle board, a shutter pivotably attached thereto, a spring engaging said shutter, a pin and a lever engaging said baffle board, said 65 pin, lever and spring means functioning to normally position said shutter in open rela-

tion to said aperture in said baffle board and whereby said aperture may be manually positioned to partially or wholly close said aperture for the purpose described.

2. In a radio apparatus and sound amplifying unit for housing radio apparatus, and comprising an irregular shaped hollow body adapted to be positioned above the floor of a room, a baffle board having an aperture, a shutter movably disposed thereto, said 70 shutter adapted to form a closure means for said aperture in said baffle board, said shutter closure providing a means for controlling the tone vibrations emitted from said radio apparatus and sound amplifying unit, substantially as described.
